UNITED STATES PATENT OFFICE

GEORGE ARTHUR BROWN, OF SALEM, MASSACHUSETTS, ASSIGNOR TO BENNETT, INCORPORATED, OF SALEM, MASSACHUSETTS, A CORPORATION OF MASSACHUSETTS

DEVICE FOR PRODUCING DISPERSIONS

Application filed April 16, 1926. Serial No. 102,552.

This invention has relation to a method of and device for producing dispersions, and more particularly dispersions of thermoplastic materials such as bitumens, gums and waxes, and has for its object to provide a method and a device for producing such dispersions in a continuous, efficient and economical manner.

While the method and device of the present invention is to be described in connection with the production of dispersions of thermoplastic material, it should be understood that the method and device may be employed for other analogous applications.

In producing dispersions of thermoplastic materials, such, for example, as are set forth in patent application Serial No. 55,063, filed September 8, 1925, by Albert L. Clapp, the process employed comprises heating and melting the material to be dispersed, and while in molten condition intimately mixing and agitating with it a heated solution of a dispersing agent, e. g., a solution of sodium silicate. The mixture is agitated for a relatively short period of time, so that substantial saponification (when the material to be dispersed is saponifiable) is not effected. To preclude such material saponification, as well as to prevent a coalescence of the dispersed particles into larger agglomerates while they are molten, the dispersion is preferably rapidly cooled immediately after it is produced to effect a congelation of the dispersed particles.

In accordance with the method of the present invention, one of the constituents of the dispersion, preferably the dispersing solution, is fed and agitated in a continuous stream and, while it is being agitated, the material to be dispersed is introduced and agitated thereinto in a continuous stream fed at a predetermined constant rate.

Broadly stated, the device for carrying out this method comprises a shell provided with agitating blades through which materials may be continuously passed, means for feeding the materials in continuous streams at predetermined constant rates into the shell, and means for regulating the relative rates of feed of such materials.

With these and other objects in view, the invention consists in certain novel features of procedure, as well as of construction, combination and arrangement of parts, as will be more fully hereinafter described in conjunction with the accompanying drawings, wherein

Figure 1 represents a front elevation of the device in combination with certain auxiliary apparatus.

Figure 2 represents a side view of the device.

Figure 3 represents in isometric view, cups for feeding the materials in predetermined, constant amount into the shell.

Figure 4 represents a section on the line 4—4 of Figure 1.

Figures 5, 6 and 7 represent sections taken respectively on the lines 5—5, 6—6 and 7—7 of Figure 4.

Figure 8 illustrates a side view, partly in section, of a preferred form of feed cup provided with means for regulating the rate of feed of material.

Figure 9 represents a plan view of the same.

Figures 10, 11 and 12 illustrate certain details thereof.

Referring to Figure 1 of the drawings, 2 represents a tank in which a supply of a thermoplastic material to be dispersed, e. g., a mixture of paraffin and rosin, is maintained in heated, liquefied state. The material may be heated and liquefied in the tank 2 by suitable heating means, as by steam coils. Or, if desired, the material may be melted in a suitable melter, and then supplied to the tank. Similarly, a supply of the dispersing solution is maintained in a tank 1. The tanks 1 and 2 are preferably respectively provided with screening partitions 13 and 113, so as to retain impurities contained in the raw materials employed.

The liquefied material and the dispersing solution are in continual streams fed at predetermined constant rates to a shell 20 in which the dispersion is effected. To this end, the material is continuously withdrawn from the tank 2 by a pump 7, forced through the pipe 8, and discharged into a feed control cup 100

9 located above and discharging into the intake end of the shell 20. An overflow pipe 7a communicates with the interior of the cup through its upper side, the material rising 5 above the outlet of the pipe being returned to the melt in the tank 2. The material is fed at a rate such that there is a continuous overflow or circulation through the pipe 7a, thus maintaining a substantially constant 10 level or head in the cup and ensuring a fluidity of the material contained therein. The bottom of the cup 9 comprises a discharge orifice of predetermined diameter, so that the material may be continuously fed at 15 a predetermined constant rate by gravity into the intake end of the shell through a discharge pipe 12.

The dispersing solution is similarly fed into the intake end of the dispersing device. 20 For this purpose, a pump 3 communicates with the tank 1, forcing the solution through a pipe 4 into a feed cup 5 arranged above the intake end of the shell. The dispersing solution is maintained at a constant level or head 25 in its cup, by an overflow pipe 10, which returns the excess solution into the tank 1. The dispersing solution flows by gravity at predetermined, constant rate through an orifice of predetermined diameter formed through 30 the bottom of the cup, thence into a pipe 6 which discharges the solution into the intake end of the shell.

In Figures 8 to 12 there is shown a preferred form of feed cup 70, which may be employed for either or both the dispersing solution and the material to be dispersed, preferably the latter at least.

The cup is provided with inner and outer side walls 71 and 72, respectively, forming 40 an annular jacket 73 about the cup, through which a suitable heating medium such as steam may be passed to aid in maintaining the material in the cup at the proper temperature for dispersion. The steam inlet and 45 outlet pipes are respectively shown at 74 and 75, and the material inlet and overflow pipes are respectively designated as 76 and 77. Provision is also made to vary readily and accurately the rate of discharge of material 50 from the cup, so that the relative proportions of dispersing solution and material to be dispersed may be adjusted as desired. This is very desirable, inasmuch as the different thermoplastic materials require varying 55 quantities of dispersing solution to effect a dispersion of the desired character. As shown, a tube 78 extends vertically and centrally through the cup, being pressed into or otherwise fixed in the bottom 79 and the top 60 98 thereof projecting beyond the wall of the cup. Rotatable within the tube 78 and closely fitted therein at its upper and lower portions but of smaller diameter at its central portion to avoid excessive friction in rotation, is a tube 79a, provided with an orifice

80, registerable to a greater or lesser degree with a corresponding orifice 81 in the tube 78 by rotation of the tube 79a within the tube 78. As shown, rotation is effected by manipulation of a lever or adjusting handle 81a, 70 within which is held the upper end of the inner tube 79a, which extends above the top 98. The handle is provided at its outer end with a portion 83 extending downwardly and thence inwardly at 83a under the rim 98a of the top. The handle 81a may be fixed in position to the top after the desired adjustment, by turning down a screw 84 threaded therethrough, thereby clamping a finger 85 pivoted to the portion 83 against the upper surface of the rim and also clamping the arm 75 in position. The finger is urged against the screw, so that when the set screw is turned up the arm may be freely turned, this action being afforded as by a tension spring 86 fixed at its upper end to the outer end of the finger and at its lower end to a pin 87 on the portion 83. A scale 88 calibrated preferably in terms of rate of discharge of material through the orifice, may be provided on the cup positioned in reading relation to the portion 83a of the arm, so that the arm may be readily set to give the desired rate of discharge through the orifice. The inner tube, together with this arm, may be withdrawn from and assembled 80 with the cup as a unit, by notching the rim as at 89 to allow the portion 83a to be passed therethrough. The cup as a whole may be supported by a bracket 90 fixed to a pipe 91 discharging into the shell 20, the material flowing from the cup through the orifice of the inner pipe, which extends and discharges 95 into the pipe.

The shell 20, as shown, is inclined to the horizontal. Within the shell there is axially mounted for rotation a propelling and agitating member, designated as a whole as 21. The member comprises a shaft 22 which is journaled at its lower end in a bearing 23 having the radial arms 24, by which it is secured to the shell 20, as by bolts 25. The shaft 22 is journaled at its upper end in a bearing 27 which fits within and is held in position by a cap 28 screwed to the upper end 100 of the shell. The shaft is provided with agitating and propelling blades 30, spaced angularly about the shaft, which are supported and fixed as by welding at spaced intervals along the shaft, by means of a series of spiders 105 31 suitably fixed thereto and defining sections or zones in the shell. The blades 30 are helicoidal in configuration and are spaced from the shaft, thus imparting a whirling or agitating in addition to a propelling motion to the materials fed into the device. Preferably, 110 the helicoidal configuration of the blades at the upper portion of the shaft 22 is steeper than at its lower portion, thus causing a more rapid agitation of the materials at the zone or section of the device where the materials 115

come together and where the dispersion is to be produced. As shown, a quarter-turn of the blades is made at the upper shorter section or zone *a* between the spiders 31 and 31*a*, whereas only a quarter-turn of the blades is made between the spiders of the longer, lower sections or zones *b*, where sufficient agitation for the prevention of agglomeration in addition to propulsion is desired.

The shaft 22 is rotated by a driving shaft 33 fixed thereto as by means of a flexible coupling 34. The shaft 33 may be driven by any suitable driving means, a motor 36 supported by the device through a bracket 37 being shown. The motor shaft 36*a* may be geared down to drive the propeller shaft 22 at the desired rate of speed, through a worm (not shown) provided at its outer end, meshing with a worm gear at the outer end of the shaft 33.

The dispersing solution is discharged from the feed control cup 5 into the device into the zone *a* immediately below the uppermost spider 31, and a rapid whirling or agitating motion is immediately imparted to the material. To secure optimum results in the production of the dispersion, I have found that the material to be dispersed is preferably intermingled with the dispersing solution while the latter is in rapid agitation. Consequently the material to be dispersed is introduced into the device above the zone in which the dispersion solution is introduced. As shown, the material to be dispersed is discharged into the shell above the uppermost spider 31. The material flowing downwardly into the rapidly agitated dispersing solution, is then rapidly agitated and mixed therewith, resulting in a dispersion. In actual operation, while the dispersion is being formed and agitated in the section or zone *a*, there is an apparent complete wall or partition formed by the rotation of the spider 31 which separates the uppermost zone of the shell into which the material to be dispersed is introduced and the zone *a* immediately therebelow, into which the dispersing solution is fed,—the material penetrating through the apparent wall into the section *a* and being rapidly whirled together with the dispersing solution.

Under certain conditions, however, the procedure may be reversed and the dispersing solution may be introduced into the shell above the uppermost spider 31 and the thermoplastic material to be dispersed may be introduced into and agitated in the zone *a* therebelow. This method entails certain disadvantages as it tends to prevent the production of a uniform dispersion or to cause a freezing or congelation of the thermoplastic material without effecting a dispersion. In other words a localized action rather than the uniform dispersive effect obtained by the first-mentioned procedure is promoted.

I have found it sometimes desirable to in-

duce into the shell at the point where the dispersion is being produced, a certain amount of steam, and have therefore provided a pipe 38 extending into the pipe 6, through which steam may be passed, along with the molten thermoplastic material, thus helping to maintain it in fluid condition. A vent opening 50 is also provided in the uppermost zone of the shell, to maintain suitable pressure conditions within the device. The downward inclination of the shell 20, along with the feeding effort afforded by the blades 21, forces the dispersion out through the shell, from which it may be received into a barrel or other suitable container.

To preclude a material saponification when saponifiable thermoplastic material is employed and also to prevent the coalescence of the discrete particles of the dispersion while molten, provision is made rapidly to cool the dispersion immediately after it is produced. To this end, a cooling jacket 51 is formed about the shell 20, as by arranging a cylindrical shell 40, of a larger diameter, thereabout, the annulus formed between the shells being sealed at its upper and lower ends by suitable sealing rings 41. Water may be continuously circulated through the cooling jacket in countercurrent flow to the movement of the dispersion. The water is introduced in regulated amount through a pipe 43, flows upwardly through the jacket and thence out through the discharge pipe 44. The discharge end of the device is thus maintained at the lowest temperature by the water, the temperature of the water rising toward the intake end of the device as the heat of the dispersion is abstracted and absorbed thereby, approaching the temperature of the dispersion at the section or zone *a* and thus aiding in maintaining the materials at the desired temperature for effective dispersion. By this means, the dispersed particles are caught or congealed in fine condition immediately after the dispersion is produced, preventing the formation of large agglomerates and also effecting the cooling of the dispersion down to a reasonably low temperature. If desired, in order to effect a dilution and further cooling of the dispersion, a certain amount of cooling water may be conducted into the shell 20 through a pipe 144. Or, if desired, other material may be introduced and incorporated into the dispersion at this point.

As previously stated, the shell 20 is arranged at an angle to the horizontal, to aid in the propulsion of the material from the device. I have found that, under ordinary conditions of operation, an angle of about 45 degrees to the horizontal permits proper rate of discharge of the dispersion, provision being made to adjust this angle according to changes of conditions. For adjusting the angle, the lower portion of the shell 40 is

provided with a lug 47, which is pivotally supported as at 48 by a column 49, and the upper portion of the shell 20 is provided at either side with a trunnion 60 journaled in a yoke 61, which is telescopically secured within a supporting column 62.

While I have described the device of this invention as being particularly applicable for the production of dispersions, it should be understood that this use is illustrative only, and that the device may be used for analogous purposes, or for any other uses for which it is found suitable.

Having thus described an embodiment of this invention, it should be obvious that various changes and modifications may be made therein without departing from its spirit or scope as defined by the appended claims.

I claim:

1. A device for continuously producing a dispersion of thermoplastic material comprising an inclined cylindrical shell, means for introducing a dispersing agent in a continuous stream at a predetermined constant rate into the upper end of said shell, means for agitating the continuous stream of agent introduced into said shell, and means for feeding molten thermoplastic material by gravity in a continuous stream at predetermined constant rate into said shell above the point of introduction of said dispersing agent, said means comprising a tank for maintaining a supply of the material, a feed cup arranged above and discharging into the upper end of said shell, means for constantly feeding an excess of molten material from said tank into said cup, and an overflow pipe communicating with the interior of said cup and returning the excess molten material into said tank.

2. A device for continuously producing a dispersion of thermoplastic material comprising an inclined cylindrical shell, means for introducing a dispersing agent in a continuous stream at a predetermined constant rate into the upper end of said shell, means for agitating the continuous stream of agent introduced into said shell, means for feeding molten thermoplastic material by gravity in a continuous stream at predetermined constant rate into said shell above the point of introduction of said dispersing agent, said means comprising a tank for maintaining a supply of the material, a feed cup arranged above and discharging into the upper end of said shell, means for constantly feeding an excess of molten material from said tank into said cup, and an overflow pipe communicating with the interior of said cup and returning the excess molten material into said tank a pipe for introducing steam into the upper end of said shell to maintain the material in molten condition, said shell having a vent at its upper end above the point of introduction of said molten material.

3. A device of the class described, comprising an inclined cylindrical shell, a shaft arranged axially within said shell, helicoidal blades supported by said shaft and spaced angularly about and from said shaft for mixing and conveying materials introduced into said shell, and means for driving said shaft.

4. A device of the class described, comprising an inclined cylindrical shell, a shaft arranged axially within said shell and journaled at its upper and lower ends in bearings fixed to said shell, helicoidal blades supported by said shaft and spaced angularly about and from said shaft for mixing and conveying materials introduced into said shell, and means located at the upper end of said shell for driving said shaft.

5. A device of the class described, comprising an inclined cylindrical shell, a shaft arranged axially within said shell, helicoidal blades supported by said shaft and spaced angularly about and from said shaft for mixing and conveying materials introduced into said shell, means for driving said shaft, and a jacket arranged about said shell.

6. A device of the class described, comprising an inclined cylindrical shell, a shaft arranged axially within said shell, helicoidal blades supported by said shaft and spaced angularly about and from said shaft for mixing and conveying materials introduced into said shell, means for driving said shaft, a cylindrical shell of larger diameter arranged about said first-mentioned shell, the annulus formed between the shells being closed at its upper and lower ends, and pipes communicating with said jacket for the circulation of a medium through said jacket in counter-current flow to the movement of the material in the shell.

7. A device of the class described, comprising an inclined cylindrical shell, a shaft arranged axially within said shell, helicoidal blades spaced angularly about and from said shaft for mixing and conveying materials introduced into said shell, a series of spaced spiders to which said blades are secured fixed to said shaft; and means for driving said shaft.

8. A device of the class described, comprising an inclined cylindrical shell, a shaft arranged axially within said shell, helicoidal blades spaced angularly about and from said shaft for mixing and conveying materials introduced into said shell; a series of spaced spiders to which said blades are secured fixed to said shaft and defining sections in said shell, means for driving said shaft, means for introducing a stream of material in predetermined constant quantity into the section below the uppermost spider, and means for introducing a stream of material in predetermined constant quantity into the shell immediately above said uppermost spider.

9. A device of the class described, comprising

ing an inclined cylindrical shell, a shaft arranged axially within said shell, helicoidal blades spaced angularly about and from said shaft for mixing and conveying materials introduced into said shell, a series of spaced spiders to which said blades are secured fixed to said shaft, means for driving said shaft, cups for maintaining supplies of material to be introduced into and mixed within said shell arranged above said shell and discharging by gravity streams of material thereinto in predetermined constant rates, means for continuously supplying said cups with material, and overflow pipes communicating with said cups for maintaining a constant level of material therein.

10. A device of the class described, comprising an inclined cylindrical shell, a shaft arranged axially within said shell helicoidal blades spaced angularly about and from said shaft for mixing and conveying materials introduced into said shell, a series of spaced spiders to which said blades are secured fixed to said shaft and defining sections in said shell, the curvature of said blades at one section of the shell into which certain of said materials are introduced being steeper than in the other sections, means for introducing other material at a predetermined constant rate into said shell above said one section, and means for driving the said shaft.

In testimony whereof I have affixed my signature.

GEORGE ARTHUR BROWN.
